UNITED STATES PATENT OFFICE.

SEIGO HASEGAWA AND TAKASHI IKEGI, OF OSAKA, JAPAN.

LOCOMOTIVE BOILER.

Application filed September 12, 1918. Serial No. 253,846.

To all whom it may concern:

Be it known that SEIGO HASEGAWA and TAKASHI IKEGI, citizens of Japan, residing at No. 5075 Tennozi, Rokumantai-cho, Minami-ku, Osaka, Japan, and No. 102 Kami-Fukushima, Kita-nichome, Kita-ku, Osaka, Japan, respectively, have invented certain new and useful Improvements in a Locomotive Boiler; and they do hereby declare the following to be a full, clear, and exact description of the invention, such as will enable others skilled in the art to which it appertains to make and use the same.

Our invention relates to improvements in locomotive boilers. The same comprises a boiler that has a steam stop valve or a regulator, not between the saturated steam space and the superheater as usual, but between the superheater and the engine cylinders or other steam consuming means, and also a steam passage extending from between the regulator and the superheater to the saturated steam space in the boiler. When the regulator operates to shut off the flow of steam to the engine cylinders, the said steam passage is automatically opened, so that the steam that has been superheated or generated in the superheater may be sent back to the saturated steam space by a positive steam circulating means. The invention has for its object to superheat or evaporate steam continuously within the superheater, even when steam is not sent to the engine cylinders; and in consequence, the efficiency of the boiler is much increased, and overheating of the superheater pipes is prevented.

Referring to the accompanying drawings, Figure 1 shows a sectional elevation of a portion of a locomotive boiler according to our invention.

Figure 2 is a sectional view of a modified boiler construction, embodying our invention.

In Figure 1, A indicates the boiler shell, and B represents the superheater pipes which run through the smoke tube D and connect the saturated steam header C with the superheated steam header E. F is a steam stop valve or regulator. When the valve F is open, steam from the superheated steam header E is let into the engine cylinders (not shown in the drawing) through the pipe G. H and J indicate a circulating steam passage which extends from a point

between the superheater and the regulator F and discharges into the saturated steam space of the boiler shell, and a suitable apparatus I is placed between the inlet of the pipe H and the outlet of the pipe J. The apparatus I is operated automatically when the regulator is closed, and stops when the regulator is open. Any suitable positive circulating apparatus may be used at I, and for purposes of illustration we have herein shown the device I to consist of a rotary blower or fluid impeller. L is a steam turbine coupled to the blower I to drive the latter. N is the steam supply pipe for the turbine L, and O is the exhaust steam pipe of the turbine. A suitable automatically acting device K is provided for automatically supplying steam to the turbine L. As herein illustrated, the device K comprises a cylinder Q; and a piston R working in the cylinder Q is coupled directly to the steam regulating valve S. A connecting pipe P establishes communication between the cylinder Q and the steam pipe G. A pipe M connects the saturated steam space of the boiler to the automatically acting valve K, which latter admits steam to the steam pipe N and turbine L, under certain conditions.

When the regulator valve F is open the steam that is generated in the boiler flows from the saturated steam header C through the superheating pipe B, superheated steam header E, and pipe G, to the engine cylinders or other steam consuming means. In this case, as the pressure in the cylinder Q is equal to that in the boiler, the valve S is not opened, because the area of the piston R is larger than that of the valve S. But when the regulator valve F is closed, the steam pressure in the pipes G and P and that in the cylinder Q drops to such pressure that the steam pressure from pipe M automatically opens the valve S, admitting steam to the pipe N. The steam passing through the pipe N into L drives the turbine, which sets the circulating means or blower I in action, causing a positive withdrawal of steam from the superheated steam header E and a discharge of such steam into the saturated steam space of the boiler, and a positive steam circulation through the superheater B. Thus, the superheated steam is carried through a passage outside the boiler, and positively circulated in a closed circuit through the saturated steam space of the

boiler, saturated steam header, tubes and superheated steam header of the superheater, and their connecting passages. The exhaust steam from the pipe O may be sent 5 into the blast or elsewhere for further use.

Figure 2 shows a modification. Similar letters of reference designate corresponding parts in both Figures 1 and 2. When the steam stop valve F is closed the superheated 10 steam header communicates with the saturated steam space of the boiler and at the same time water is allowed to flow into the superheating tube B, so as to allow the superheater to act as a steam generating 15 tube.

I is a valve placed in the passage connecting the saturated steam header with the superheated steam header. When the regulator is closed, the valve is to be opened 20 automatically or by hand. X is a valve placed in the pipe connecting the steam header C with the water space of the boiler. It is so located that when the valve is open, water from the boiler flows into the header 25 C. Y is a valve in the pipe located at the lowest part of the superheated steam header E, which is used to drain off the water in the spaces B, C, and E.

When the regulator F is closed and the 30 valve I is open, the steam begins to circulate in the headers E and C and also in the pipe B; and the said pipe B continues to act as a superheater as described. If the valve X is open, in this case a portion of the water 35 in the boiler enters the pipe B and the pipe B ceases to serve as a superheater tube, but acts as a steam generating tube. When the regulator F is to be opened again, the valve Y must first be closed and the valve 40 Y opened to drain off the water in the spaces C, B and E.

In the above description, the water supply pipe leading to the space C communicates 45 with the water space in the boiler, and the drain pipe which leads from the header E is open outside of the boiler as stated, but the former may draw in water from the outside of the boiler by means of an injector or by some other feed water supply 50 apparatus, while the latter may eject the drain into the water space of the boiler by means of a similar device.

While, for purposes of illustration, we 55 have herein shown and described our improved boiler in detail, it is to be understood that various features thereof may be modified without departing from the spirit of our invention, and therefore we do not wish to be limited to the exact arrangement and 60 details herein disclosed.

We claim—

1. The combination with a boiler having a superheater provided at its receiving end with a saturated steam header and at its 65 discharge end with a superheated steam

header, of valve controlled means for supplying steam from said superheated steam header to steam-consuming means, means connecting the discharge and receiving ends of said superheater, and means in said connecting means for causing a positive circulation of steam through said superheater when the supply to said steam-consuming means is shut off. 70

2. The combination with a boiler having a superheater provided at its receiving end with a saturated steam header and at its discharge end with a superheated steam header, of means for supplying steam from said superheated steam header to steam-consuming means, means connecting the discharge and receiving ends of said superheater and means in such connecting means for causing a positive circulation of steam 75 through said superheater, said last mentioned means being automatically rendered operative when the supply to said steam-consuming means is shut off. 80

3. The combination with a boiler, of a superheater connected to the saturated steam space thereof, a pipe for connecting said superheater to steam-consuming means, a valve in said pipe, means connecting the discharge side of said superheater to the saturated steam space of the boiler, and automatically acting fluid impelling means 90 in such connecting means for causing a positive circulation of steam through said superheater when said valve shuts off steam supplied by the superheater to said steam-consuming means. 95

4. The combination with a boiler, of a superheater connected to the saturated steam space thereof, a pipe for connecting said superheater to steam-consuming means, a valve in said pipe, means connecting the discharge side of said superheater to the saturated steam space of the boiler, and steam operated fluid impelling means in such connecting means for causing a positive circulation of steam through said superheater 100 when said valve shuts off steam supplied by the superheater to said steam-consuming means. 105

5. The combination with a locomotive 110 boiler having a saturated steam space and a superheated steam space, of superheated tubes connected to said steam spaces, means for controlling the flow of steam from said superheated steam space to steam-consuming means, means for conducting fluid in a closed circuit through said superheater tubes and said steam spaces, and means for positively causing a circulation of fluid in said closed circuit when said controlling means 120 shuts off the flow of steam to such steam-consuming means. 125

6. The combination with a boiler having a saturated steam space and a superheated steam space, of superheater tubes connected 130

- to said steam spaces, means for supplying steam from said superheated steam space to steam-consuming means, means connecting the superheated steam space to the saturated steam space of the boiler for withdrawing steam from said superheated steam space and delivering it to said saturated steam space, automatically acting fluid impelling means in such connecting means for causing 10 a positive circulation of steam through said superheater tubes, and means for automatically supplying steam to operate the impelling means when the supply to said steam-consuming means is shut off.
- 15 7. The combination with a boiler having a saturated steam space and superheated steam space, of superheater tubes connected to said steam spaces, a delivery pipe connect- ing said superheated steam space to steam-consuming means, a valve in said delivery pipe, a circulating steam pipe connecting the superheated steam space to the saturated steam space of the boiler, automatically acting fluid impelling means in said circulating steam pipe, a fluid-pressure pipe extending from said delivery pipe at a point between said valve and said steam-consuming means and automatically acting means including a fluid-pressure actuated element in said fluid-pressure pipe for effecting a 20 supply of steam to operate said impelling means when said valve is shut.
- 10 15 In testimony whereof they hereunto affix their signatures.

SEIGO HASEGAWA.
TAKASHI IKEGI.
